INVENTOR:

John B. Perkins
Joseph A. Miller & Co.

UNITED STATES PATENT OFFICE.

JOHN B. PERKINS, OF TAUNTON, MASSACHUSETTS.

SHAWL-STRAP.

SPECIFICATION forming part of Letters Patent No. 349,899, dated September 28, 1886.

Application filed February 25, 1886. Serial No. 193,110. (No model.)

To all whom it may concern:

Be it known that I, JOHN B. PERKINS, of Taunton, in the county of Bristol and State of Massachusetts, have invented certain new and useful Improvements in Shawl-Straps, of which the following is a full, clear, and exact description, reference being had to the accompanying drawings, forming part of this specification.

10 My invention relates to the class of devices, ordinarily known as "shawl-straps," which have binding cords or straps fixed to a handle which is mounted in a frame, the said straps serving to secure the shawl or package.

15 The objects of my invention are to render more efficient and simple and to cheapen this class of devices.

To the above purposes my invention consists in the certain new and peculiar construction and arrangement of the essential parts of the device, as hereinafter fully described and claimed.

20 In the accompanying drawings, Figure 1 represents a perspective of my improved device. Fig. 2 represents a sectional view of Fig. 1, taken on a plane cutting the handle and frame lengthwise and vertically through their centers, and with the straps shown in portions. Fig. 3 represents a partial view, in section and in full, of a modified form of my device. Fig. 4 represents an end view of Fig. 3.

In the said drawings like numbers designate like parts throughout.

Referring to the drawings, 5 designates the 25 frame, with its surfaces flat and in the main is straight, with the oblong slots 6, parallel and in pairs, disposed near the ends of said main part. The ends of frame 5 are bent uprightly, and have the eyes 7 correspondingly located and in alignment. The tie-rod 8 is 30 mounted in the eyes 7, and at one end has a fixed head, which takes against the outside of the frame, and at the other end is screw-threaded to receive the thumb-nut 9, which binds against the outside of the frame. Upon 35 the tie-rod 8, and within the upright ends of frame 5, is loosely mounted the two-part handle 10 11. These parts 10 and 11 are similarly made, being spindle-shaped, with the hubs 12 40 at the outer ends, and having the central channel, 13, for the reception of tie-rod 8. The

parts of the handle 10 11 come flatly together at their inner ends, as at point 14, and are freely rotary in either direction upon the tie-rod 8. The straps 15 and 16 are alike, of the 55 same length, and are passed through the slots 6 in frame 5, so as to be looped on the under side of said frame, as shown, to receive the shawl or package and bind the same. The free ends of straps 15 and 16 are fastened, end 60 to end, upon the hubs 12, which are reel-shaped, to allow room for the said straps to be wound around them.

From this description of the construction of the device it is obvious that when the thumb-nut 9 is loosened, so as not to bind against the frame 5, the parts 10 and 11 of the handle are each rotary independently and in the same or opposite directions, each part thereby winding its attached strap upon its hub, as desired. By 65 this construction the straps 15 and 16 can each be regulated by itself as to the size of the loop by turning the respective parts 10 and 11 of the handle. When these parts 10 and 11 have been turned to adjust the loops of the straps 70 as desired, the thumb-nut 9 is then turned so as to bind tightly against the frame 5, thereby compressing the parts of the handle 10 11 together at the point 14, and holding them immovably in the desired position by virtue of 75 the tie-rod 8.

In Figs. 3 and 4 I have shown two modified features of the device. I use in this form, in place of the thumb-nut 9, the cam-lever 17, which has three limbs, as shown, the forked 80 pair of which are hinged upon pintles upon the nut 18, which works on the screw-threaded end of tie-rod 8. The nut 18 is adjusted properly to give the cam-lever 17 just enough play to bind against the frame 5 and compress the 85 parts 10 and 11 of the handle together against displacement by turning on the tie-rod 8. In Fig. 3 the cam-lever 17 is shown in binding position, and when it is to be released the lower upturned end of the same is lifted out 90 from the frame and carried up beyond the tie-rod 8, so as to pass the point of the cam action of said cam-lever. When it is desired to bind the parts of the handle again, the cam-lever is pressed down in position shown in 95 Figs. 3 and 4.

In the modified form I have interposed be-

tween the inner ends of the parts 10 and 11 of the handle the concavo-convex washers 19, which are mounted on tie-rod 8, and serve to give a slight spring action in compressing and releasing said parts, thereby avoiding the dead-pressure, and giving easier action to the device. These washers may be of any suitable well-known material—such as rubber, leather, or cork—or as an equivalent to the washers, a spring of metal may be used.

It is evident that the straps 15 and 16 may be adjusted by means of their respective parts of the handle, so as to have one form a large loop and the other a small one, in order to accommodate and secure a package or bundle of irregular shape or size, and then the parts can be compressed together into fixed position by the action of the tie-rod and binding means before described.

20 My invention provides a simple, efficient, and durable device, that is easily and quickly adjusted to secure irregularly-shaped bundles. The straps may of course be differently arranged and still be equivalent to that shown by me. For instance, only one end of the strap may be fastened to the hubs, while the other may be fastened to the frame or wound thereon suitably.

25 In constructing the device I preferably make the frame, the rod, and the thumb-nut of metal, the two-part handle of wood, and the straps of leather. However, these materials may be changed as desired.

30 There may be various modifications made in the several parts of my device without substantially departing from the spirit of the invention herein described and claimed.

35 I am aware of the heretofore use of a two-part or divided handle in bundle-holders, and hence do not broadly claim such as my invention.

40 Having thus described my invention, I claim as new and desire to secure by Letters Patent—

1. In combination, a transversely-divided handle and straps therefor, a tie-rod extending loosely and entirely through said handle in the axial line thereof, a binding device at one end of said tie-rod, whereby the parts of said handle may be rotated independently upon said rod or bound together immovably, substantially as described. 45

2. In combination, a transversely-halved handle having an interposed yielding washer, straps for said handle, a tie-rod extending loosely and entirely through said handle in the axial line thereof, and a three-sided frame whose opposite uprights support the respective ends of said tie-rod, provided at one end with a fixed head, at the other end with an adjustable nut, whereby the halves of said handle may be independently rotated or rigidly bound together, substantially as described. 55

3. The combination, with the frame 5, of the tie-rod 8, set in said frame, and the thumb-nut 9, and of the two-part handle 10 11, provided at the outer ends with the holding-straps 15 and 16, respectively, substantially as described. 60

4. The combination, with the frame 5, provided with the slots 6, and having the upright ends perforated at 7, of the tie-rod 8, provided with the thumb-nut 9 and set in said perforations 7, and the two-part handle 10 11, provided with the reel-like hubs 12 and channels 13, and the straps 15 and 16, affixed to said hubs and passing down through said slots 6 in the frame, all substantially as and for the purpose described. 70 75

In witness whereof I have hereunto set my hand.

JOHN B. PERKINS.
